UNITED STATES PATENT OFFICE.

HENRY J. NOACK, OF SPOKANE, WASHINGTON.

PULLER FOR BATTERY TERMINALS.

Application filed December 22, 1926. Serial No. 156,394.

This invention relates to a device for pulling the terminals from battery posts, one of the objects being to provide a simple, compact and inexpensive tool of this character which can be used without pressing on the battery and injuring it. Frequently the posts become corroded so that it is practically impossible to loosen the bolt holding the collar upon the posts. The terminals 10 have sometimes been removed by heating them with a torch but this frequently injures the battery.

An object of the present device is to provide a tool which can be quickly applied to 15 the terminal, readily actuated to provide sufficient force to withdraw the terminal from the post, there being no danger of injuring the battery in any way during this operation.

With the foregoing and other objects in view which will appear as the description proceeds, the invention resides in the combination and arrangement of parts and in the details of construction hereinafter described 20 and claimed, it being understood that changes in the precise embodiment of the invention herein disclosed may be made within the scope of what is claimed, without departing from the spirit of the invention.

In the accompanying drawings, the preferred form of the invention has been shown.

In said drawings,

Figure 1 is a front elevation of the terminal puller in position.

Figure 2 is a side elevation thereof.

Figure 3 is a central vertical section through the puller, the screw and its nut being shown in elevation and the terminal being also shown in elevation.

Figure 4 is a view partly in plan and partly in section of the device.

Referring to the figures by characters of reference A designates the usual battery post on which is clamped a collar B from which 45 extends the terminal C. The tool constituting the present invention includes a sheet of metal bent to provide a channeled body 1 having a central opening 2. Fitted within the central portion of the channel is a nut 3 and this nut is held in place by offsetting the sides of the channeled body inwardly as

at 4 so that the body cannot lift relative to the nut nor the nut drop out of position. Longitudinal displacement of the nut is prevented by striking the metal inwardly adjacent opposed faces of the nut as shown at 55 5. Rivets 6 or the like are extended transversely within the end portions of the channeled body as indicated at 6 and mounted to swing on these rivets or pivot devices are 60 tongues 7 each having a sleeve 8 at its upper end engaging the rivets while its lower end is bent to provide a hook 9. A screw 10 extends through the nut 3 and has an angular head 11 at its outer end whereby it can 65 be turned readily with a wrench.

In using the device the body 1 is placed above the post A and the hooks 9 are swung toward each other so as to engage under the opposed ears E extending from the collar 70 B. Screw 10 is then fed against the end of the post and by applying sufficient force to the head thereof with the use of a wrench, the body 1 can be caused to pull away from the post, dragging with it the collar B. 75 Thus the collar with the terminal wire extending therefrom can be disconnected from the post A without subjecting the battery to pressure and without requiring the use of a heating torch or other means likely to 80 injure the battery.

Importance is attached to the particular way in which the nut is assembled with the body 1 inasmuch as this enables the structure to be made very cheaply and at the same 85 time prevents the parts from becoming separated and lost when not in use.

What is claimed is:

1. A terminal puller for batteries including a longitudinally channeled body, tongues 90 pivotally connected to the end portions of the body and having terminal hooks, a nut firmly seated within the channeled body, there being inwardly offset portions formed by the walls of the body for holding the 95 nut against movement relative to the body, and a pressure screw extending through the nut and body.

2. A terminal puller including a longitudinally channeled body, pivot devices extending transversely of the end portions thereof, tongues mounted to swing on the 100

pivot devices and having hooks at their free ends, a nut seated within the middle portion of the body, the sides of the body being offset inwardly to hold the nut against displacement in one direction, there being inwardly offset portions of the sides of the body adjacent the nut for holding said nut

against longitudinal displacement relative to the body, and a pressure screw extending through the nut and body.

In testimony that I claim the foregoing as my own, I have hereto affixed my signature.

HENRY J. NOACK.
